DIAPHRAGM FOR MODEL PASSENGER CARS

Clifford H. Smith, Chicago, Ill., assignor to American Model Engineers, Chicago, Ill., a corporation of Illinois

Application August 2, 1934, Serial No. 738,105

11 Claims. (Cl. 46—48)

My invention relates to a flexible diaphragm for use on miniature railway passenger cars in simulation of the diaphragms which connect the vestibules of adjacent passenger cars on modern railroad trains.

In some of its general objects my invention aims to provide a simple, easily manufactured and inexpensive diaphragm which can readily be attached to an end of a miniature (or so-called model) of a railway passenger car, and which will simulate the appearance of the diaphragms used on actual railway cars without requiring a complete bellows construction.

In addition, my invention aims to provide a flexible diaphragm for this purpose which will present perforated end plates parallel and in alignment with each other when the diaphragm is supported from the end attached to one car, which will automatically be compressed when two such diaphragms are interposed between car ends spaced by a distance less than the normal joint thickness of the two diaphragms, and which will readily flex and skew after the general manner of the diaphragms used on passenger trains to adjust itself to variations in the relative positions of the end faces of the adjacent cars.

More particularly, my invention aims to provide a flexible diaphragm in which two rigid end plates are connected by a suitably folded strip of cloth which simulates a bellows, and in which the outer end plate is supported independently of the cloth from the inner end plate in such a manner as to prevent the cloth from sagging downward.

Still further and also more detailed objects will appear from the following specification and from the accompanying drawing, in which drawing

Fig. 1 is a fragmentary perspective view of an end of a model passenger car equipped with a flexible diaphragm embodying my invention, with the diaphragm somewhat distended to clarify the drawing.

Fig. 2 is a plan view of two such diaphragms on the adjacent ends of two cars as they appear when the cars are rounding a curve, the car portions being indicated in dotted lines.

Fig. 3 is a central, vertical and longitudinal section through one of the flexible diaphragms before it is attached to a car.

Fig. 4 is a vertical section taken along the line 4—4 of Fig. 3.

Fig. 5 is a fragmentary plan view of the cloth

blank from which the flexible part of one of the diaphragms was formed, drawn on a smaller scale than Figs. 1 to 4 and with dotted lines indicating the fold lines.

Fig. 6 is an end view, showing the folded cloth strip as it appears while being slid between the two end plates after these plates have been connected by the lower spring and before the upper spring is attached.

Fig. 7 is a plan view showing one of my flexible diaphragms as it appears when digitally distorted to permit access for fastening an end plate to a car.

In its here illustrated form, my miniature flexible diaphragm consists of two counterpart frame-like, rigid and upright end plates 1, two counterpart spiral springs 2 secured at their opposite ends to the said end plates and extending respectively at higher and lower elevations than the apertures 3 in the end plates, and a suitably perforated imitation diaphragm of cloth interposed between the two end plates.

Each end plate 1 is desirably punched from a thin sheet of brass, with its aperture 3 of a bore which in general simulates that through that of the bellows diaphragm on a real passenger car, and each spring 2 desirably is a spiral coil presenting parallel ends which can readily be soldered respectively to the opposed faces of the two end plates. Moreover, both of these springs preferably have their axes in the medial vertical plane P (Fig. 4) of the faces of the end plates, and each spring is of a considerably smaller diameter than the height of the horizontal frame members of the two end plates to which the ends of the spring are soldered or brazed.

For the flexible part of each diaphragm, I first provide a strip of cloth corresponding in width to the extreme height h of the counterpart metal end plates, trim one longitudinal edge of this strip to consecutive V-formations each corresponding in its width and shape to the upper edge of one of the end plates, and provide the other longitudinal edge of this cloth strip with recesses R^1 respectively opposite the apices A of the said V-formations on the first-named edge of the cloth. Each of these lower recesses R^1 preferably has a semi-circular upper portion of a diameter only slightly larger than that of one of the springs 2, and has a height fully as great as that diameter.

Then I also punch the cloth strip with generally rectangular perforations 5 each of which has a common upright axis a with an apex A at one edge of the cloth and with the upright center line of the bottom recess R^1 on the opposite edge.

of the cloth, and I provide each perforation 5 with an upward extension U which is a counterpart of a bottom recess and also has its axis *a* alining with that of bottom recess.

5 When the thus formed strip of cloth is then folded back and forth about fold lines F (Fig. 5) midway between the consecutive axes *a*, each portion of the cloth strip between the consecutive fold lines forms panels or perforated leaves each of which corresponds in contour and bore to both of the metal end plates 1, except for the bottom recesses R¹ and the perforation extensions R in the cloth panels, the consecutive leaves or panels being connected to each other only at their side edges.

In assembling one of my flexible diaphragms, the two springs 2 may first have their similar ends soldered to one of the end plates, respectively adjacent to the mid-length of the upper and lower frame members of that end plate, and the free end of the lower spring then soldered to the lower frame member of the other end plate. The zig-zag-folded cloth strip is then slid partway downward between the two end plates, as shown in Fig. 6, the central part of the upper frame member of one end member is exposed through the bore or panel opening 3 in the other end member, so that the free end of the upper spring can readily be soldered to the first-named end member.

30 When the resulting partial assembly is then turned over, the assembler can then reach the other end of the spring (through the alined apertures in the cloth panels and through the aperture in the panel to which the upper spring has already been soldered) so as to solder the other end of the upper spring to the adjacent end member.

As soon as the solder has cooled, the folded cloth strip can then be slid farther downward, so that the two springs are respectively housed by 40 and bear upwardly against upper edge portions of the aperture extensions R¹ and the bottom recesses R¹ in (or substantially all of) the cloth panels.

Then, by digitally flexing each diaphragm, as 45 shown for example in Fig. 7, the assembler can readily secure access both to the end faces of the zigzagged (imitation bellows) cloth strip and to an inner face of a metal end member for cementing each end face of the bellows-simulating cloth 50 to the adjacent end member.

In the resulting assembly (shown in section in Fig. 3) the two springs then cooperate to prevent a downward sliding of all of the cloth panels which are between the two end panels, and the interfitting of the two springs with the recesses in the cloth prevent each such panel from shifting or 55 rocking sidewise. Moreover, each coiled spring when each of a normal length considerably greater than the joint thickness of the cloth panels tends 60 to keep the flexible diaphragm considerably distended and with its end plates parallel to each other, as shown in Fig. 3.

In using such a flexible diaphragm on a model car 7, one metal end plate of the diaphragm is 65 fastened flatwise to the end of the car. This may be done with glue or cement, or I may provide the metal end plate with perforations 4 (as shown in Figs. 4 and 6) so that it can be fastened to a car end by drive pins extending through such 70 perforations and through correspondingly pricked perforations in the end panels of the folded cloth.

With two of my flexible diaphragms thus fastened to the adjacent ends of two model cars, a connecting of these cars (in the usual manner 75 well known to users of model railway equipment)

by a coupler of shorter effective length than the normal joint thickness of the two diaphragms, such a coupling will somewhat compress the diaphragms so as to keep their adjacent end plates pressed against each other. This contacting of the merely spring-supported end plates continues when the cars are rounding curves, since the springs readily adjust themselves to a departure from parallelism between the two end plates of one of my flexible diaphragms. Thus, Fig. 2 10 shows how the folds of each simulation of a bellows are brought closer to each other at the inner side of a curve, but spread farther apart at the outer side.

Moreover, since each coiled spring readily permits its axis to be curved in any direction, my diaphragm construction also allows the diaphragms to adjust themselves to vertical as well as lateral displacements of one car from the other, so that each diaphragm can readily skew 20 when one car sways with respect to the other on an uneven track. However, during all such actions, the engaging of the springs with wall portions of the recesses in the cloth panels through which the springs extend limits the 25 bodily movement of these panels to portions close to the springs, leaving other portions of the cloth panels free to flex somewhat back and forth so as to enhance the resemblance to a flexible vestibule bellows on a real passenger car.

So also, it will be obvious from Fig. 1 that the springs are substantially concealed from view even when one of my diaphragms is on a loose car, and that my simple folded strip of cloth effectively simulates a bellows although much more 35 simple and inexpensive than a true bellows which would require at least three separate cloth portions for its construction.

However, while I have described my invention in connection with an embodiment including 40 numerous desirable details of construction and arrangement, it is to be understood that these might be varied in many respects without departing either from the spirit of my invention or from the appended claims, and that my invention also is not to be limited as to the above-described assembling procedure.

I claim as my invention:

1. A vestibule bellows comprising a plurality of upright leaves consecutively hingedly connected to each other at alternately opposite side edges; two rigid end members respectively fastened flatwise to the outward faces of the two end leaves, the said leaves and the end members having alined apertures; and two resilient means extending respectively adjacent to the upper ends of said apertures and the lower ends of the said leaves, each of the said resilient means being fastened at its ends respectively to the two end members.

2. A vestibule bellows as per claim 1, in which the apertures in the said leaves consist of perforations having alined upward extensions jointly housing the upper of the resilient means, and in which the said leaves have downwardly open alined recesses disposed below the said perforations and jointly housing the lower of the resilient means.

3. A vestibule bellows comprising a plurality of upright leaves consecutively hingedly connected to each other at alternately opposite side edges; two stiff end members respectively fastened flatwise to the outward faces of the two end leaves, the said leaves and the said members

having alined perforations; and coiled springs extending through the said leaves respectively above and below the perforations in the leaves, each of the coiled springs being fastened at its 5 ends respectively to the two end members; the said perforation extensions and the said recesses alining vertically to permit the said hinged connected leaves to be slid conjointly downward with respect to the said end members before the

10 said end members are fastened to the latter.

4. A vestibule bellows as per claim 1, in which the said hinged connected leaves consist of a single strip of flexible material doubled back and forth along parallel and equally spaced lines at 15 right angles to the axis of the strip.

5. A vestibule bellows as per claim 1, in which the said hinged connected leaves consist of a strip of flexible material doubled back and forth along parallel and equally spaced lines at right 20 angles to the axis of the strip, and in which each of the said members is a frame-like and flat metal plate.

6. A vestibule bellows comprising two upright, parallel and frame-like metal end plates presenting horizontal upper and lower frame members; two spirally coiled springs respectively connecting mid-width portions of the upper and lower frame members of the said end plates; and 25 a zigzagged strip of flexible cloth interposed between the said end plates and presenting leaves consecutively connected to each other at their side edges, the two end leaves of the said zigzagged strip being respectively fastened to the 30 two end plates and the said leaves having apertures alining with the bores of the frame-like end plates.

7. A vestibule bellows as per claim 6, in which

each of the said end leaves is secured flatwise to the metal end plate adjacent to it.

8. A vestibule bellows as per claim 6, in which the said leaves of the cloth strip have alined and downwardly open recesses respectively at the lower edges of the aperture in the leaves and at the lower edges of the leaves, through the upper and lower of which recesses the two coiled springs respectively extend. 5

9. As a constituent for a flexible bellows-simulating member for a vestibule bellows, a strip of cloth provided with uniformly spaced, parallel and generally rectangular counterpart apertures, each aperture having at one end a central extension of relatively small width and height in 10 proportion to the width of the aperture, and the said strip having outwardly open edge recesses of counterpart size with the said aperture extensions; each of the said recesses alining transversely of the strip respectively with the said 15 aperture extensions and opening at the opposite edge of the strip from that toward which the said aperture extensions present their closed ends. 20

10. A vestibule bellows as per claim 3, in which the said perforation extensions and the said recesses each have the upper portions of their walls engaging one of the coiled springs, whereby the 25 said springs cooperate in supporting the leaves of the bellows which are disposed between the said two end leaves. 30

11. A vestibule bellows as per claim 3, in which the said perforation extensions and the said recesses each have wall portions thereof disposed for laterally engaging one of the coiled springs 35 to limit a lateral shifting of the leaves of the bellows which are disposed between the said two end leaves.

CLIFFORD H. SMITH.
